(57) CLAIM

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The broken lines immediately adjacent to the shaded area represent unclaimed boundaries of the design. The five eyelet regions demarcated by broken lines in the shaded area and the broken lines showing the remainder of the shoe, are for environmental purposes only and form no part of the claimed design.
